UNITED STATES PATENT OFFICE.

FRED E. KLING, OF YOUNGSTOWN, AND LUTHER B. WEIDLEIN, OF CLEVELAND, OHIO.

VIBRATING MECHANISM.

1,400,169.

Specification of Letters Patent. Patented Dec. 13, 1921.

Application filed January 13, 1921. Serial No. 436,992.

To all whom it may concern:
Be it known that we, FRED E. KLING and LUTHER B. WEIDLEIN, citizens of the United States, and residents of Youngstown, in the county of Mahoning and State of Ohio, and Cleveland, in the county of Cuyahoga and State of Ohio, respectively, have invented certain new and useful Improvements in Vibrating Mechanisms, of which the following 10 is a specification.

This invention relates to vibrating or shaking apparatus, and more particularly to apparatus for use in vibrating or shaking filter mats in dry gas cleaners.

15 In practice it has been found desirable, if not necessary, in order to effectively remove the foreign particles of ore, dust, etc., from the filter mats of dry gas cleaners by vibration, to strike the under side of the mat, and 20 with this object in view the present vibrating mechanism was devised.

Another object of the invention is to provide a vibrating mechanism having a spring accelerated action, thus providing a short 25 snappy vibratory stroke.

A further object of the invention is to provide a device of this character wherein the casing or stand will have little or no shock or strain from the vibrating parts, and 30 whereby reaction of the shock is absorbed by the reciprocating members and springs.

Other objects and advantages of the invention will be more fully brought out in the following specification, and illustrated 35 in the accompanying drawings in which—

Figure 1 is a sectional side elevation of our improved vibrating or shaking mechanism applied to the filter mat of a dry gas cleaner. Fig. 2 is a sectional side elevation taken

40 on the line II—II of Fig. 1.

Fig. 3 is a transverse section taken on the line III—III of Fig. 2.

Referring particularly to the drawings, the letter A designates the stand or casing of 45 the device which is approximately cylindrical in shape and houses the actuating mechanism.

A cylindrical reciprocating plunger B, which is mounted within the casing, has a 50 removable top or cap 2, the longitudinal side slots 3, and the apertured bottom 4.

A power driven shaft 5 is journaled in bearings 6 formed on the casing A and passes through the slots 3 in the plunger 55 B. An eccentric 7 is rigidly mounted on the

shaft 5 and engages a bearing 8 having diametrically oppositely arranged protuberances 9 and 9'. The top or cap 2 of the plunger and its bottom 4 each have annular protuberances or shoulders 10 and 11, respectively, centrally arranged and on a line with the protuberance on the bearing 8.

A coil spring 12 is mounted within the plunger B and bears around the protuberance 11 on the bottom, and protuberance 9 65 on the eccentric. A second coil spring 13 is mounted within the plunger above the eccentric 7 and bears around the protuberance 10 on the top, and protuberance 9' on the eccentric. 70

A plunger rod 15 which passes through the bottom of the plunger B, is adjustably secured in place by the split locking collar 16 and clamping bolts 16', and extends downwardly through a stuffing box 17 and gland 75 formed in the bottom plate of the stand or casing A.

The lower end of the rod 15 passes freely through an aperture in the yoke 18 to which the filter mat 19 is rigidly secured, and the 80 rod 15 has a hammer head 20 secured thereto in any desired manner. The hammer head 20 is adapted to engage with the seat or anvil 21 formed around the aperture in the yoke. 85

The construction and arrangement of the 85 apparatus is such that the hammer only engages the seat 21 on the upward stroke of the rod 15 and plunger B.

It will be understood that filter mat 19 may be of any approved construction, but is usually inclosed within a frame member, and is adapted to be supported within the gas cleaner by I-beams 22 or other suitable supports. 90

The operation of the device is as follows— 95

The shaft 5 being rotated by a suitable source of power will revolve the eccentric member 7 within the bearing 8. Starting with the eccentric member at dead center, it will be moved downward, compressing the 100 lower spring 12, which, in turn, transmits the energy to the reciprocating mass formed by the plunger B, rod 15, and hammer 20. This transmission of energy will cause the plunger B and its associated parts to move 105 downward, compressing the upper spring 13, and when the eccentric has passed its lowest point, the kinetic energy of the parts will be released to the action of the compressed spring 13, and the reciprocating parts will 110

be rapidly reversed and thrown upward until the hammer 20 strikes the seat 21 of the yoke 18 with a quick snappy blow. Immediately the cycle of operations is again commenced. The springs 12 and 13 serve to produce the quick snappy action of the reciprocating parts and to absorb the shock or vibration caused when the hammer 20 strikes the seat 21, thus relieving the casing 10 or stand A from this strain.

We claim:

1. A vibrating device comprising a casing, a cylindrical plunger member mounted within said casing, means for guiding said plunger within said casing, a rotary shaft journaled in bearings on said casing and passing through said plunger, an eccentric mounted on said shaft, a bearing mounted on said eccentric, a spring member having its one end abutting said bearing and its other end abutting the top of said plunger, a second spring member having its one end abutting said bearing and its other end abutting the bottom of said plunger, the rotation of said eccentric being adapted to actuate said springs to cause a reciprocation of said plunger.

2. The combination with a filter mat having a yoke extending above its upper surface, of a vibrating mechanism comprising a casing, a reciprocating cylindrical plunger mounted within said casing, a plunger rod secured to said plunger and extending downward through an opening in said yoke, a head on said rod adapted to strike said yoke when said rod is reciprocated, an eccentric mounted on a shaft journaled in said casing, a bearing adapted to be actuated by said

eccentric, and a yieldable connection between both ends of said plunger and said bearing.

3. The combination with a filter mat having a yoke extending above its upper surface and having a centrally arranged aperture therein, of a vibrating mechanism comprising a casing, a reciprocating cylindrical plunger mounted within said casing, a plunger rod secured to said plunger and extending downward through said aperture in said yoke, a head on said rod adapted to engage a seat formed on said yoke around said aperture when said plunger and rod are reciprocated, and means for reciprocating said plunger.

4. The combination with a filter mat having a yoke extending above its upper surface and having a centrally arranged aperture therein, of a vibrating mechanism comprising a casing, a reciprocating cylindrical plunger mounted within said casing, means for guiding said plunger within said casing, a plunger rod adjustably secured to said plunger and extending downward through said aperture in said yoke, a head on said rod adapted to engage a seat formed on said yoke around said aperture when said plunger and rod are reciprocated, a shaft journaled in said casing, an eccentric mounted on said shaft, a bearing carried by said eccentric, and spring members connecting the top and bottom surfaces of said plunger with said bearing.

In testimony whereof we have hereunto set our hands.

FRED E. KLING.
LUTHER B. WEIDLEIN.
